UNITED STATES PATENT OFFICE.

HARRY G. TURNER, OF CHICAGO, ILLINOIS.

ENGRAVING MACHINE.

Application filed September 8, 1922. Serial No. 598,910.

To all whom it may concern:

Be it known that I, HARRY G. TURNER, a citizen of the United States, residing in Chicago, Cook County, Illinois, have invented 5 certain new and useful Improvements in Engraving Machines, of which the following is a specification.

These improvements relate to engraving machines, and are exemplified herein more 10 particularly as pertaining to that type of engraving machines in which lines are formed on a coated plate by means of a needle-like stylus or graver whereby the surface of the plate is exposed in lines constituting the 15 design to be reproduced and the plate being thus prepared for an etching process with acid, the etched plate being used for reproducing the design. Such etched plates and the printing operations employing them are 20 well known, and it has been suggested heretofore also to provide mechanical devices whereby the operator may move a tracer by hand upon a desired design on a pattern plate such as illustrated herein and thus 25 cause the movement of a stylus or graver over the surface of a coated plate for the general purpose mentioned. The use of a pantograph device in engraving machines is not novel at this time.

30 The general objects of the present improvements as applied to devices of the type illustrated herein are to simplify, cheapen and render more easy and rapid the transferring of designs to such coated plates for 35 the ensuing etching operation. More specific objects and advantages will appear hereinafter.

In the accompanying drawings, which 40 form a part of this specification, Figure 1 is a perspective, partly broken away, of the device complete in a highly advantageous embodiment; Fig. 2 is an enlarged fragmentary detail showing a rack and pinion connection shown in Fig. 1; Fig. 3 is a perspective 45 of an adjustable plate holding member; Fig. 4 is a fragmentary vertical sectional view of table parts on about the line 4 of Fig. 1; Fig. 5 is an enlarged front view of the tracer head; Fig. 6 shows the parts of 50 Fig. 5 as viewed at right angles thereto; Fig. 7 is an enlarged front view of the graver head; Fig. 8 is a top view thereof; Fig. 9 is a view at right angles to the view of Fig. 7, and Fig. 10 is a fragmentary face 55 view of a lay-out strip which may be considered as of paper.

The various mechanisms are shown as being mounted on a horizontal table 15 which will preferably be supported at ordinary table height from the floor whereby the 60 operator may sit comfortably while at work. The supporting arm 16, in my practice a casting, extends so as to overlie the table and is provided with upper and lower pivot bearings to accommodate the ends of the vertical 65 supporting rod 17 for easy rocking movement therein. A pantograph device is carried for swinging movements in horizontal planes upon this rod 17, as by securing the mounting 18 to the rod 17 by means of the 70 set screw 20. The mounting 18 and therefore the pantograph device as a whole may be adjusted in vertical directions and held at any desired relative elevation by the screw 20. Such vertical adjustment of the pantograph as a whole is advantageous in initially 75 assembling the device and also from time to time according to plates or other objects of different thicknesses respectively operated upon and provides for the use of tracers and 80 gravers of different lengths.

Two rods 21 and 22, one above the other, materially spaced apart and extending parallel with each other, are rigidly secured to the mounting 18 and constitute one arm of 85 the pantograph. The yoke-like member 23 is slidably mounted on these two rods and may be held in any desired relative position by the set screw 24. An arm support 25 is pivotally mounted on a vertical axis upon 90 the yoke 23, and the pantograph arm or rod 26 is slidably mounted in the support 25 and may be held in any desired relative 95 position by the set screw 27. The front end of the rod 26, Fig. 9, is rigidly secured to a mounting 28 which is vertically bored to receive slidably the graver rod 30. This mounting 28 is mounted for rocking movements on a vertical axis in the frame 31, Fig. 7, by means of a pair of cone bearing members 32 and 33 adjustably mounted in the frame 31 whereby the desired precision of movement at the connection may be maintained.

100 Rigid with the frame 31 is the pantograph arm 34, the free end of which is carried by a supporting member 35, Fig. 1, which is mounted for horizontal rocking movements on the vertical axis 36 in the frame or mounting 37, the set screw 38 being adapted to hold the rod 34 and mounting 35 in any desired relative position.

The fourth pantograph rod member 40 passes through the frame member 37 and is held by the set screw 39, and at its other end it is rigid with the supporting member 41 which is mounted for horizontal rocking movements on the vertical axis 42 in the frame 43, to which frame are also secured, and in rigid relation thereto, the rods 21 and 22.

10 The several pivotal connections at 27^a, 36, 42 and at the ends of the rod 17 may be considered to be of the cone-and-socket type shown at 32 and 33 in Figs. 7 and 9.

From the foregoing description of the 15 pantograph elements it will be noted that the pantograph as a whole is sustained in its normally horizontal position by the spaced apart rods 21 and 22 which in turn are held by the vertical rod 17, and also that the 20 various pantograph rods or members are so connected to each other that they will have the usual pantograph movements. The markings on the several rods shown in Fig. 1 are graduations by which the effective 25 length of the pantograph members may be increased or decreased in predetermined amounts.

The front end of the rod 40 is rigidly secured to a supporting member 45, Fig. 6, 30 which is vertically bored to accommodate for sliding movements therein the rod 46 held adjustably by the set screw 49, the rod 46 having the cross-piece of insulating material 47 secured thereto by a pair of screws 48. The insulation 47 carries a pair of binding posts 50—50 and also a pair of spring arms 51—51 with which the binding posts respectively are in electrical communication, each arm 51 having a block of insulation 52 at its lower end portion and each having its lower end bent inward with the metal of the spring contact arms 51 exposed at 53 on the plane of the inner surface of the insulating blocks 52. The lower end of the 45 rod 46 is axially bored and tapped at 54 to accommodate the upper end of a screw-threaded tracer-holding rod 55 which may be threaded into the rod 46 adjustably and held in any given position of adjustment 50 by the thumb nut 56 on the threaded rod 55, the nut being adapted to jam against the lower end of the rod 46. A contact collar 57 is slidably mounted upon the lower end portion of the rod 46 and is provided with 55 a pair of oppositely-disposed handle bars 58. A coiled spring 60 between the thumb nut 56 and the collar 57 maintains the collar in a raised relative position when the device is not in actual operation. The collar 57 60 has an annular enlargement 61 at its upper end against which the insulating blocks 52 press when the collar is in its raised position. When downward pressure is applied to the handle bars 58 the collar 57 is lowered 65 and the rib or annular projection 61 then

contacts the extremities 53 of the spring contact members 51 whereby electrical current may pass from one contact member to the other. A pin 62, Fig. 5, limits the upward movement of the collar 57. The lower end of the rod 55 is recessed at 63 to receive the end of the tracer 64, which may be an ordinary steel phonograph needle and which is held in place by the set screw 65.

Turning now to Figs. 7, 8 and 9, the 75 graver 30, usually provided with a diamond point at the bottom, projects loosely through the support 28 and the bearings 32 and 33 therefor and its upper end portion is screw threaded to receive the adjusting thumb nut 70 and is provided with a diametric saw cut at 71, Fig. 9, to accommodate upper and lower arms 72 and 73 pivoted respectively at 74 and 75 in the vertical support 76 rising from the frame 31. A weight 77 is held in 80 various positions of adjustment on the arm 72 by the set screw 78. The arm 73 carries the armature 80 of a pair of electro-magnets 81. A spring 82 maintains the armature 80 away from the pole faces of the magnets 81 when the magnets are not energized, and since the arm 73 is below the nut 70 the spring 82 also maintains the point of the graver 30 in raised relative position when 85 current is not flowing through the magnets 90 81. The adjustment of nut 79 on the rod 79 determines the amount of vertical relative movement the graver 30 shall have. From Fig. 7 it will be noted that should current be passed through the magnets the armature 80 95 100 would be lowered and that the graver 30 would thereby be induced to move downward, partly through its own gravitational action and partly through the action of the weight 77, and that according to the relative 105 position of the weight 77 on the rod 72 the downwardly-directed force acting upon the graver 30 will be greater or less.

Electrical conduits 83 and 84 are shown as being connected to the binding posts 50, Fig. 1, and one of these as 84 will be understood as leading to a battery B diagrammatically shown; that the other thereof as 83 leads to the binding post 85, Fig. 7, and is thereby placed in electrical communication with the coils of the magnets 81; and that another connector as 86 leads from the battery and is connected to the binding post 87, Fig. 7, which is also in communication with the coils of the magnet 81, the arrangement being such that when the handle bars 58, Fig. 5, are lowered, the circuit of the battery is completed through the magnet coils, and this action results in a simultaneous lowering of the graver when the handle bars associated with the tracer are downwardly moved.

Upon the table 15 is provided a pair of parallel guides 90 extending from left to right. On these guides 90 the platform 91 is mounted for sliding movement in the di- 100 105 110 115 120 125

rection of the guides. On the platform 91 is rigidly mounted a pair of guides 92 extending at right angles to the guides 90, and on the guides 92 is slidably mounted the plate-holding table 93. This table 93 is provided with a plurality of apertures 94 adapted to accommodate the pins 95 of the stop or holding bar 96 whereby this stop 96 may be positioned to accommodate plates of different dimensions. The screw-operated clamp 97 is adapted to press against the front edge of the plate 98 whereby the plate is held tightly between the clamp and the stop 96. The movement of the plate-holding table 93 on the guides 92 provides for adjusting the work with respect to the various lines of words, etc., to be engraved thereon.

A rack 100 is pivotally connected at 101 to the platform 91, this rack passing over any selected one of three pinions 102, 103 and 104, Fig. 2, on the shaft 105 journaled in bearings on the main table 15. The rack 100 is held in engagement with the particular pinion selected by means of the cone-pulley-like roller 106 on the arm 107 drawn downward by the spring 108. The rack 100 is mounted at 101 to permit of its being moved laterally so as to travel upon any of the three pinions mentioned. At the other end of the shaft 105 there are mounted a plurality of pinions such as 110, 111, 112, etc., of gradually increasing diameters respectively and the sliding rack 113 is adapted to engage with any of the pinions 110, 111, 112, etc. To accomplish this the rack 113 is mounted slidably in a carrier 114 which is mounted slidably upon the shaft 115 which is journaled at each end portion in brackets downwardly extending from the main table 15. A coiled spring 116 draws the upper part of the carrier 114, and with it the rack 113, toward the pinions 110, 111, etc. The shaft 115 carries a pinion 117 held between a pair of extensions 118, one of which is shown in Fig. 1, through which extensions 118 the shaft 115 rotatably projects. The shaft 115 has a key-way 120 and it is to be understood that a key carried by the loosely mounted pinion 117 slides in the key-way 120 whereby the rotation of the shaft 115 will rotate the pinion 117.

The construction and arrangement thus next hereinabove described is such that when the shaft 115 is rotated in the clockwise direction as viewed from in front of the machine the pinion 117 moves the rack 113 downward and, through its engagement with one of the gears 110, 111, etc., the shaft 105 is rotated in the same direction and the rack 100 is moved so as to draw the platform 91 and with it the plate 98 to be engraved towards the right as viewed in Fig. 1.

The wheel 122 is held upon the outer end of the shaft 115 by the clamping hand wheel 123. By loosening the clamp 123 the wheel

122 may rotate freely on the shaft. The wheel 122 carries the gear 124 with which meshes a worm 125 on the shaft 126. A hand lever 127 enables the operator to rotate the wheel 122 in one direction or the other. The wheel 122 has its outer periphery on cylindrical lines, and this outer periphery projects through an opening at 128 in the main table 15. The table 15 has a forward extension 130 adapted to receive a flat pattern plate 131, which rests against a guide block 132 and is held by a spring-pressed clamp 133 which is released through a simple system of levers including the knee-piece 134 normally adjacent to a knee of the operator. By pressing against the lever 134 the clamp 133 is raised, releasing the pattern plate 131 for longitudinal movement or removal from the machine.

In view of the foregoing description the operation of the device may be described as follows: Let us assume that the operator desires to trace upon the prepared plate 98 the words "Milk products." He first takes his pattern plate such as 131, which contains depressed letters, places the pattern plate before him on a table or bench, takes a strip of paper 135, Fig. 10, and lays off on this strip of paper the respective widths of letters to be used as shown by the pattern plate. For instance, the small marks 136 and 137 (Fig. 10) indicate the distance found to exist between the dotted lines on each side of the letter M on the pattern 131. Likewise the marks 137 and 138 (Fig. 10) indicate the distance between the dotted lines on each side of the letter I (shown as being engaged by the tracer on the pattern plate 131). In the same way the operator lays off on the paper strip markings of respective letter spaces which indicate the total amount of space occupied by the letters as shown by the pattern plate, including the desired space between words, and as the operator goes along laying out the markings on the paper strip 135 (known as the lay-out strip), he marks on each successive space on the strip the letter which that space represents. Thus reading from right to left the space and the letters on the lay-out strip 135 are for the words "Milk products." The lettering on the strip may be roughly done, but the space markings such as 136, 137 and 138 should be accurately done so as to have the lettering properly spaced apart in the finished work.

The strip 135 is then secured upon the periphery of the wheel 122, as by means of any suitable adhesive on the underside of the lay-out strip near its ends. The plate 98 to be engraved is clamped in its desired position. The pattern plate is next clamped in position with the letter M opposite the opening 128 in the table, and the tracer is placed in the right-hand space mark associated 130

with the letter M, this mark being shown by a dotted line on plate 131. Then by means of the hand lever 127 the plate 98 is moved laterally until the desired place for beginning the line is reached. The hand-nut or clamp 123 is then released and the wheel 122 is freely turned, without turning the shaft 115, by turning the hand-lever 127 in one direction or the other, until the letter M 10 on the lay-out strip comes opposite the letter M on the pattern plate, with one of the marks 136 or 137 opposite the corresponding mark shown by dotted lines at the sides of the letter M on the pattern plate 131. Owing 15 to the curvature of the strip 135 as it is positioned on the wheel 122 the lines 136 and 137 will not accurately coincide with the corresponding marks on the pattern plate, and it is therefore preferable to work from only 20 one of the marks 136 or 137, and preferably the first one in the order of movement, that is, mark 136 for the letter M, mark 137 for the letter I, mark 138 for the letter L, etc. Having then brought the mark 136 opposite 25 the corresponding mark associated with the letter M on the pattern plate the hand clamp 123 is tightened and thereafter remains tightened until that line is engraved. The result of such tightening is that for every 30 movement of the wheel 122 the work plate 98 will be moved, and in the same direction as the wheel 122 moves at the top.

It may be mentioned in this connection that if the wheel 122 were inadvertently 35 moved too far in the clockwise direction as viewed from in front it is preferable to move it in the anti-clockwise direction farther back than the spacing of the letters indicates so that it may again be moved clockwise 40 whereby the letters on the lay-out strip are always brought up to the exact place desired by the same kind of movement of the wheel 122. This is because all such mechanisms have a certain amount of play or lost 45 motion, especially where gears are employed, and by using the same movement of the wheel 122, as clockwise, to advance the various parts in their respective progressive movements disparities in the engraving due 50 to such slight but unavoidable looseness will be avoided.

The next step is to locate the work plate 55 as 98 in the direction of the guides 92. The tracer is placed in the lowermost part of the design of the letter M, that is, at the place corresponding to the position shown as being occupied by the tracer in the letter I in Fig. 1. The plate to be engraved is then moved by hand on the guides 92 until the desired 60 position of the same part of the letter M is directly beneath the graver point 30.

In the ensuing engraving operation the operator rests his hands on the handle bars 65 58 forcing them downward and making electrical contact at 53, Fig. 5, as hereinabove

explained, inducing downward movement of the graver 30 into contact with the work plate 98. It may be mentioned here that the tracer 64 is moved into the recess defining the pattern to be reproduced against the 70 springiness of the pantograph arms and connections. Ordinarily this tracer point 64 will be away from the surface of the pattern plate a very small distance, say about a sixty-fourth of an inch. The spring 75 60, Fig. 5, has sufficient strength to develop the desired springiness of the pantograph arms and connections whereby when downward pressure is applied to the handle bars the first action is to move the tracer point 80 into the design to be traced, and thereupon additional pressure upon the handle bars forces the collar 57 downward so as to make the electrical contacts at 53 respectively and the collar enlargement 61. The movement 85 of the tracer is through such a short distance that adjustments could be made whereby the electrical contact is made before the tracer actually reaches the bottom of the groove defining the design, or the parts 90 could be so adjusted that the tracer normally rests at the bottom of the design, in which case it would be lifted from one letter to another by upward pressure on the handle bars. 95

Since the distance for the tracer to be moved downwardly is very slight, the result in my actual practice is that substantially simultaneously with the depression of the contact collar 61 the tracer 64 comes into 100 the bottom of the design to be traced, and thereupon the operator simply moves the tracer point 64 in the groove or grooves of the pattern plate defining that letter.

At the same time, due to the electrical contact made as hereinabove mentioned, the diamond point of the graver 30 contacts the work plate, and, through the pantograph movements, the desired design is marked upon the prepared plate, exposing the metal 105 for the etching process. The amount of descent to be provided for the graver 30 is determinable by the position of the adjusting nut 79 of Fig. 7. It is mentioned that according to the construction illustrated the 110 descent of the graver may be a very small amount, indeed, for instance, a thirty-second of an inch or less, and this is important since if the graver were to strike the work with a considerable impact it 115 would make a mark at the point of contact other than the very fine one which might be desired.

Having reproduced the letter M the clamp 123 is released and the pattern plate is 120 moved to bring the letter I into position to be traced. In doing this the most advanced of the space indicating lines as 140 for the letter I is brought opposite the most advanced marking, namely 136 for the 125 130

letter M. (This position is not illustrated.) The plate 131 is then clamped in that position and the wheel 122 is next moved clockwise so that the mark 137 of the lay-out strip comes opposite the mark 140, as shown. This movement of the wheel 122 caused a corresponding movement of the work plate 98, and thereupon the letter I may be traced. The wheel 122 is then allowed to remain quiescent while the pattern plate is again moved so that the most advanced space marking for the letter L, that is, the line 141, comes opposite the line 137 on the lay-out strip, and thereupon the pattern plate is held fast and the mark 138 on the lay-out strip is brought opposite the mark 141 by turning the wheel 122. In the same way all of the letters are successively reproduced.

20 Since the pantograph is capable of reproducing the design in relatively large or relatively small form means are provided for moving the work plate 98 various amounts relative to the amount of movement of the periphery of the wheel 122. These means include the various gears 110, 111, 112, etc. and the rack 113. It is evident that if the rack 113 were operatively in engagement with the gear 111 the movement of the plate 98 would be greater with a given movement of the periphery of the wheel 122 than if the rack 113 were in engagement with the larger gear 110.

Means for further adjusting the amount of movement of the work plate under a given movement of the periphery of the wheel 122 include the three gears of different sizes shown in Fig. 2, according to which the amount of plate movement may be varied several times between that which would be provided by simply shifting the rack 113 from one to the next adjacent one of the gears 110, 111, 112, etc. That is to say, if, for instance, the rack 113 were in engagement with the gear 111 and the rack 100 were in engagement with the gear 102, and then the rack 113 were moved into engagement with the gear 110 thus causing the plate 98 to move say, for instance, an eighth of an inch less with a given movement of the wheel 122, then if the rack 100 were moved into operative contact with the pinion 103 the distance which the plate 98 would move would be less than the assumed eighth of an inch, and if the rack 100 were moved into contact with the pinion 104 the movement of the work plate would be still less than the assumed eighth of an inch. According to these means an exceedingly fine and close adjustment may be had of the movement of the work plate relative to that of the wheel 122.

60 The pattern plate may have its letters of any convenient size, say an inch to two inches in width, while the engraved result

may have its letters only a sixteenth of an inch in width or less. The adjustments of the pantograph arms determines size and other characters of the letters while the adjustment of the racks 100 and 113 with the respective gears determines the proportionate spacing of the letters and the length of the engraved line.

It may be pointed out that with a given pattern plate such as 131 showing pattern letters in ordinary form a great variety of letters may be produced through the action of the pantograph. That is to say, the letters reproduced may be relatively low and wide, or they may be relatively narrow and high, or they may be of the same form as shown by the pattern plate, or they may be caused to slant in one direction or the other, and in all instances in a multitude of sizes and degrees.

Another highly important feature of the device is in the fact that the tracer always operates in a small locality. This is not only a great advantage from the standpoint of ease and celerity of production, the operator being enabled to sit comfortably at his work and perform all of his movements immediately before him in this small locality, but it is highly important also from the standpoint of the results since the pantograph is always operating in what may be termed its normal position or within its accurate range. The engraving is therefore free from distortions due to operating the pantograph at its extreme limits.

According to my own construction of the device a continuous line 11 inches long may be engraved without resetting the lay-out strip or changing the location of the work. This indicates that it is simply a matter of size and proportions to provide a device capable of engraving lines of substantially any length desired as a substantially continuous operation.

Another important feature is in the fact that the work plate and the tracer are on the same or substantially the same horizontal plane, giving the operator full control of the instrument and rendering the result on the pattern plate visible to him at all times. According to my construction the graver is about 15 inches from the tracer. The operator may remain seated not only until a given line is engraved but until the entire plate is finished, and be constantly in view of the results.

Another important advantage is in the fact that the graver is always in its normal vertical position with respect to the plate to be engraved and is never obliged to assume a slanting position which would militate against the results.

Since the graver is automatically raised by the spring 82, Fig. 7, when contact is broken by allowing the handle bars 58 to

rise, the operator is saved much work which exists in cases where the graver must be removed from the work by hand or by a foot pedal. Furthermore the automatic 5 and substantially instantaneous movement of the graver away from the work renders it substantially impossible for the operator to deface the plate by making a scratch therein. Relatively unskilled operators 10 can use the present machine with safety to the work and at a relatively high rate of production. The fact that the pattern plate may be moved and adjusted so readily decreases the labor involved and increases the 15 output in a given time.

An important feature of the construction is in the fact that the operator, having his tape in position on the wheel 122, can adjust the machine in an exceedingly brief 20 space of time for any particular length of line desired on a plate within the limits of the construction. Knowing the length of this line as it is to appear on the plate it is only necessary for him to move the plate 25 by means of the hand lever 127 until the graver is over the beginning of the line, then adjust the wheel 122 by means of the hand lock 123, without moving the work, so that the beginning of the tape is at the normal 30 starting point at the top of the wheel, and then clamp and turn the wheel until the end of the tape is reached. If such turning has moved the plate too far or not far enough the racks 113 and 110 are shifted by 35 a simple movement of the hand and a second trial is made. By means of the close adjustment provided by the parts shown in Fig. 2 it is only a matter of one or two trials before the exact adjustment is had. 40 This eliminates a large amount of slow and tedious measuring and computation heretofore necessary.

Having thus determined the length of line the operator may vary the height or other 45 character of the letters according to the adjustments of the pantograph. Since the pantograph is an instrument well known no particular instruction needs to be given in regard to its adjustments to provide any 50 desired results; but it may be observed that the pantograph arms may be marked with a scale such as indicated on these arms respectively in Fig. 1 whereby particular results may be had by adjustments made according to the several scales. If the pantograph be set for distortion of the engraved 55 letters the distortions will be relatively the same for each succeeding letter owing to the fact that the tracer is always operated in a small central area. Another valuable feature is that such distorted letters will appear 60 on the work in a straight line.

It will be apparent to those skilled in the art that various changes, modifications and 65 departures may be made from what is here-

in specifically illustrated and described within the spirit of the invention, and reference should be had to the appended claims to determine what I contemplate as being included in the invention thus set forth. 70

I claim:

1. In an engraving machine, the combination of means forming a pantograph having a tracer and a graver, means for holding in an operative relation to the graver the material to be engraved, means for holding in an operative relation to the tracer an object having the design to be traced, the tracer being mounted for movement by hand toward and away from the object having the design to be traced when such object is held in its operative relation to the tracer, hand-operable means for moving the tracer, the graver being mounted for movement toward and away from the material to be engraved when such material is held in its operative relation to the graver, and means including said hand-operable means and an electro-magnet for inducing movement of the graver into contact with such material 80 properly positioned after the tracer has been moved into contact with the design properly positioned and by a further movement of said hand operable means, and for inducing movement of the graver away from such material when said hand operable means are movable in the reverse direction. 85

2. In an engraving machine, the combination of means forming a pantograph substantially horizontally disposed and having a tracer and a graver, each substantially vertically disposed, means for holding in an operative relation to the graver the material to be engraved, means for holding in an operative relation to the tracer an object having the design to be traced, the tracer being mounted for movement by hand toward and away from the object having the design to be traced when such object is held in its operative relation to the tracer, hand-operable means for moving the tracer, the graver being mounted for movement toward and away from the material to be engraved when such material is held in its operative relation to the graver, and means under the control of said hand-operable means for releasing the graver for gravitational movement into contact with such material properly positioned after the tracer has been moved in contact with and by a further movement of said hand-operable means, the design properly positioned, and for withdrawing the graver away from such material when said hand-operable means are moved in the reverse direction. 100

3. In an engraving machine, the combination of means forming a pantograph having a tracer and a graver, means for holding a plate to be engraved in a plane substantially parallel with the plane of the pantograph 105 110 115 120 125 130

- device and in an operative relation to the graver, means for holding a pattern plate in an operative relation to the tracer and in a plane substantially parallel with the 5 plane of the pantograph device, a pattern plate so held, the pattern plate having space markings thereon defining the width of various designs thereon which may successively be traced, means for holding a lay-out strip 10 for movement relative to the pattern plate when the pattern plate is held in a given position for use, the pattern plate being mounted for adjusting movements relative to the tracer when the tracer is in a given operative 15 position, said lay-out strip having space markings thereon substantially corresponding with space markings on the pattern plate, the lay-out strip having between adjacent of its space markings indications of 20 the subject matter to be engraved, which indications indicate particular designs upon the pattern plate between corresponding space markings thereon, the arrangement being such that the pattern plate may be 25 moved so as to bring any particular design thereon to a given position in the vicinity of the tracer at a given relative position of the tracer and the lay-out strip may then be moved to bring a corresponding indication opposite such particular design with a 30 space marking on the pattern plate corresponding to a space marking on the lay-out strip, and means under the control of the movement of the lay-out strip for moving 35 the holder for the plate to be engraved whereby with each successive and progressive movement of the lay-out strip the holder for the plate to be engraved will also be successively and progressively moved.
- 40 4. In an engraving machine, the combination of means forming a pantograph having a tracer and a graver, a pattern device for the tracer to operate upon, a movable holder for a lay-out strip, shiftable means for holding in association with the graver a plate to be engraved, and means for simultaneously shifting the holder for the plate to be engraved and for moving the lay-out-strip holder.
- 45 5. In an engraving machine, the combination of means forming a pantograph having a tracer and a graver, a pattern device for the tracer to operate upon, a rotatable holder having an arcuate surface adapted to accommodate a layout strip, shiftable means for holding in association with the graver a plate to be engraved, and means under the control of the rotative movement of the lay-out-strip-holder for shifting the 55 plate holder.
- 60 6. In an engraving machine, the combination of means forming a pantograph having a tracer and a graver, a pattern device for the tracer to operate upon, a rotatable holder having an arcuate surface adapted to accommodate a lay-out strip and arranged to exhibit a portion thereof closely adjacent to said pattern device, shiftable means for holding in association with the graver a plate to be engraved, and means for simultaneously moving the plate holder and for rotating the lay-out strip holder.
- 65 7. In an engraving machine, the combination of means forming a pantograph having a tracer and a graver, a shiftable holder for holding in association with the graver a plate to be engraved, means for adjustably holding a pattern plate whereby various portions thereof may be brought to a common relative position to be operated upon by the tracer, means for holding a lay-out strip for movement relative to that part of the pattern plate which is at such common relative position, and means under the control of the movement of the lay-out-strip-holding means for shifting the holder for the plate to be engraved.
8. In an engraving machine, the combination of means forming a pantograph substantially horizontally disposed and having a tracer and a graver each substantially vertically disposed, a shiftable substantially horizontally disposed holder for holding in association with the graver a plate to be engraved, means for adjustably holding a pattern plate substantially horizontally in association with the tracer, a wheel rotatably mounted on a substantially horizontal axis for holding a lay-out strip for arcuate movement relative to the pattern plate, and means for simultaneously moving said wheel with a rotative movement and for shifting the holder for the plate to be engraved.
9. In an engraving machine, the combination of means forming a pantograph substantially horizontally disposed and having a tracer and a graver each substantially vertically disposed, a shiftable substantially horizontally disposed holder for holding in association with the graver a plate to be engraved, means for adjustably holding a pattern plate substantially horizontally in association with the tracer, a rotatable wheel for holding a lay-out strip for arcuate movement relative to the pattern plate at a given place on the pattern plate, means for simultaneously moving said wheel with a rotative movement and for shifting the holder for the plate to be engraved, the tracer and the graver each being mounted for relative movement toward and away from the pattern plate and plate to be engraved respectively, tracer-moving means, the graver being mounted to move by gravitation toward the plate to be engraved, means for withdrawing the graver out of contact with such plate, and means under the control of

the movements of the tracer-moving means toward and away from the pattern plate for controlling the movements of the graver respectively toward and away from the 5 plate to be engraved.

10. In an engraving machine having a tracer and a graver and means for moving the tracer by hand toward and away from a design to be traced, the combination there- 10 with of electrical means including a normally open circuit and a make-and-break-contact device controlled by the movement of the tracer-moving means toward and away from the design to be traced for inducing 15 respective movements of the graver toward and away from the object to be engraved.

11. In a pantograph type of engraving machine having a tracer and a graver and 20 means for moving the tracer by hand toward and away from a design to be traced, the graver being mounted for relative movement toward and away from the object to be engraved, the combination therewith of 25 electrical means including a normally open circuit and a make-and-break-contact device controlled by the movement of the tracer- moving means toward and away from the design to be traced and also a magnet con- 30 trolling the movements of the graver toward and away from the object to be engraved, for causing the graver to move toward the object to be engraved when the tracer-moving means are moved toward the 35 design to be traced.

12. In an engraving machine, the combination of a substantially vertically-disposed graver adapted to be moved toward and away from the object to be engraved, spring 40 means for holding the graver releasably in elevated position out of contact with the object to be engraved, and magnet means for releasing the graver from the sustaining action of said spring for gravitational move- 45 ment into contact with the object to be engraved.

13. In an engraving machine, the combination of a substantially vertically-disposed graver adapted to be moved toward 50 and away from the object to be engraved, means for holding releasably the graver in elevated position out of contact with the object to be engraved, a normally open circuit, and a magnet in said circuit for releas- 55 ing said graver-holding means, the arrangement being such that energizing the magnet releases the graver for gravitational movement into contact with the object to be engraved.

60. 14. In an engraving machine, the combination of a substantially vertically-dis- posed graver adapted to be moved toward and away from the object to be engraved, spring means for holding the graver releas- 65 ably in elevated position out of contact with

the object to be engraved, an electro-magnet for releasing the graver from the sustaining action of said spring for gravitational movement into contact with the object to be engraved when the magnet is energized, 70 a hand-operable tracer, and means under the control of the operator's hand while in position to move the tracer for making an electrical contact to energize the magnet to release the graver. 75

15. In an engraving machine, the combination of means forming a pantograph having a tracer and a graver, a shiftable holder for a plate to be engraved by the graver, and means for shifting the plate holder, 80 said last-mentioned means including a rack, a gear meshing therewith, and means for rotating the gear.

16. In an engraving machine, the combination of means forming a pantograph 85 having a tracer and a graver, a shiftable holder for holding a plate to be engraved by the graver, a hand-rotatable shaft, and adjustable means for shifting the plate holder various amounts relative to a given amount 90 of rotative movement of the hand-rotatable shaft.

17. In an engraving machine, the combination of means forming a pantograph having a tracer and a graver, a shiftable holder for holding a plate to be engraved by the graver, a hand-rotatable shaft, a lay-out-strip-holding wheel on said hand-rotatable shaft, and means under the control of said 95 hand-rotatable shaft for shifting the plate holder. 100

18. In an engraving machine, the combination of means forming a pantograph having a tracer and a graver, a shiftable holder for holding a plate to be engraved by the graver, a hand-operable lay-out-strip-holder adapted to be moved relatively to bring various portions thereof successively to a common relative position, and means 105 under the control of the movements of said lay-out-strip-holder for shifting the plate holder various amounts relative to a given amount of movement of the lay-out-strip-holder. 110

19. In an engraving machine, the combination of means forming a pantograph having a tracer and a graver, a shiftable holder for holding a plate to be engraved by the graver, a hand-operable lay-out-strip-holder adapted to be moved relatively to bring various portions thereof successively to a common relative position in the vicinity of the tracer, and means for holding a pattern adjustably so as to bring its several parts to be traced into a relatively small area in the vicinity of the tracer, the arrangement being such that the tracer may always operate in a given relatively small area. 115 120 125
